CHAIR

George W. Young, Flushing, N. Y., assignor to
 R. H. Macy & Co. Inc., New York, N. Y., a corporation of New York

Application June 18, 1942, Serial No. 447,485

3 Claims. (Cl. 155—108)

This invention relates to reclining chairs and has for its object the provision of improved means for varying the inclination of the back of the chair.

In accordance with my invention I provide each back post of the chair with an inclined slot and each side of the pivoted back frame with an oppositely inclined adjacent slot. A cross-bar, adjustably mounted within the back frame, terminates in pins, each of which lies within one pair of adjacent slots. When the cross-bar is in its uppermost position the pins lie at the upper ends of the slots, each pair of slots forms, in projection, an inverted V, and the back frame is in one limiting position. When the cross-bar is in its lowermost position the pins lie at the lower ends of the slots, each pair of slots forms, in projection, an upright V, and the back frame is in the other limiting position. To raise and lower the cross-bar and thus vary or adjust the inclination of the back of the chair, I preferably utilize the frame of a sliding footrest which is housed within the base of the chair when not in use. The rear ends of the side rails of this frame are provided with sloping cam faces which engage rods depending from the cross-bar. Movement of the footrest raises or lowers the rods and the cross-bar and thus changes the inclination of the back.

In the accompanying drawing I have illustrated a chair embodying a preferred form of my invention. In the drawing Figure 1 is a vertical longitudinal section through the chair, taken along line 1—1 of Figure 2, showing the footrest housed within the base of the chair, and the back in its forward or upright position; Figure 2 is a transverse section taken along line 2—2 of Figure 1; Figure 3 is a view similar to Figure 1, but showing the footrest extended and the back in reclining position, and Figure 4 is a fragmentary horizontal section taken along line 4—4 of Figure 1.

The chair illustrated in the drawing comprises a base 1, a seat 2, arms 3 and an adjustable back 4 comprising a frame 5 and a backrest 6. The base supports at the rear of its sides a pair of back posts 7, between which the back frame 5 is pivotally mounted at 8. Housed within the base is a footrest comprising a frame 9, the side rails of which are slidably mounted within guides 10, and a collapsible footrest proper 11. The seat is provided with the usual removable cushion 12.

The inner upper face of each back post 7 is provided with an upwardly and forwardly extend-

ing slot 13, and the sides of the back frame 5 adjacent these slots are provided with similar, but oppositely inclined slots 14. Lying between the sides of the frame 5 is a horizontal cross-bar 15 terminating in pins 16 each of which extends into one pair of slots 14 and 13. Depending from cross-bar 15 are two rods 17 passing through guides 18 on the base and engaging, in the position shown in Figure 1, the side rails of the footrest. This engagement with the footrest holds the rods 17, the cross-bar 15 and the pins 16 in their uppermost position with the pins 16 lying within the upper ends of the slots 13 and 14 which, as shown in Figure 1, converge to form, in projection, an inverted V.

When the footrest frame is extended, as shown in Figure 3, support for the rods 17 is removed, whereupon the cross-bar and its pins drop into the position shown in Figure 3 and the back frame swings to the rear to occupy the reclining position shown in that figure. In this position the pins 16 lie within the lower ends of the slots 13 and 14 which converge to form, in projection, an upright V. When the footrest frame is extended, the footrest proper should be swung upward into operative position, as shown in Figure 3.

To restore the chair from the reclining position, shown in Figure 3, to the upright position shown in Figure 1, the footrest proper 11 is collapsed and the footrest frame shoved into the base. The rear ends of the side rails of the frame 9 are provided with sloping cam faces 19 which engage the lower ends of the rods 17 as the frame 9 is moved to the rear, and raise them and the cross-bar 15. This causes the pins 16 to travel upwardly in both pairs of slots 13 and 14 until they reach the position shown in Figure 1 at the upper ends of those slots. In this position the rods 17 have passed up the cams 19 and rest at the upper ends of the cams upon the side rails of the frame 9, as shown in Figure 1.

There is usually sufficient looseness of fit between the pins 16 and the slots 13 and 14, and between the rods 17 and their guides 18 to permit the parts to adjust themselves to their different positions and this play permits easy adjustment of the several parts. Because of the weight of the cross-bar 15 and the slightly rearward slope of the back frame 5 when the parts are in the position shown in Figure 1, withdrawal of the footrest ordinarily causes the back to swing into reclining position under the influence of gravity.

The chair of my invention is simple in con-

struction and operation. There is nothing to get out of order and the back can easily and quickly be changed from upright to reclining position and back again.

I claim:

1. A chair comprising a pair of back posts, a back frame pivotally mounted adjacent the posts, an inclined slot in each post, slots in the sides of the frame adjacent the slots in the posts and oppositely inclined, a cross-bar extending between the sides of the frame, pins on the cross-bar, each extending into a pair of adjacent slots, a rod extending downwardly from the cross-bar, and a movable cam in the chair engaging the rod to raise and lower the cross-bar and vary the inclination of the back frame.

2. A chair comprising a base, a pair of back posts at the rear of the base, a back frame pivotally mounted on the base adjacent the posts, an inclined slot in each post, slots in the sides of the frame adjacent the slots in the posts and oppositely inclined, a cross-bar mounted between the sides of the frame, pins on the cross-bar, each extending into a pair of adjacent slots, a footrest

frame slidably mounted in the base, cams on the rear of the footrest frame and rods extending downwardly from the cross-bar and engaging the cams, movement of the footrest frame raising and lowering the cross-bar and varying the inclination of the back frame.

3. A chair comprising a base, a pair of back posts at the rear of the base, a back frame pivotally mounted on the base between the posts, a slot in each post, inclined upwardly and forwardly, slots in the sides of the frame one adjacent each slot in the post and oppositely inclined, a cross-bar mounted between the sides of the frame, pins on the cross-bar, each extending into a pair of adjacent slots, a footrest frame slidably mounted in the base, downwardly and rearwardly sloping cams on the rear of the side rails of the footrest frame, rods extending downwardly from the cross-bar and engaging the rails, movement of the footrest frame raising and lowering the cross-bar and varying the inclination of the back frame.

GEORGE W. YOUNG.
